UNITED STATES PATENT OFFICE

GUSTAV J. SENGBUSCH, OF MILWAUKEE, WISCONSIN

PEN SOCKET MOUNTING

Application filed October 30, 1929. Serial No. 403,590.

This invention relates to desk sets of the type which consists of a base and a socket for receiving and holding a pen in a conveniently accessible position. This invention relates more particularly to an improved means for mounting the socket on the base so as to permit adjustment of the socket in both horizontal and vertical planes to the desired position.

The objects of the invention are to provide a mounting of the class described which will facilitate adjustment of the pen socket in both horizontal and vertical planes; to provide a mounting which permits a wide range of adjustment and which is not restricted to said predetermined adjusted positions; to provide a mounting which is simple in construction, easy and economical to manufacture, and neat in appearance while being durable and serviceable; and in general, it is the object of my invention to provide an improved mounting of the class described.

Other objects and advantages of my invention will be understood by reference to the following specification and accompanying drawings in which I have illustrated a desk set including a base and a pen receiving socket adjustably secured to the base by means of a mounting embodying a selected form of my invention.

In the drawings:

Fig. 1 is an end elevation of the desk set;

Fig. 2 is a fragmentary sectional view on an enlarged scale, the section being taken on a plane extending through the axis of the socket and parallel with the end elevation of Fig. 1;

Fig. 3 is a section on the line 3-3 of Fig. 2, and

Figs. 4 and 5 are perspectives of certain elements of my improved mounting.

Fig. 6 is a diagram illustrating the arrangement of the pivotal connection between the pen socket and base, the dimensions in this view being exaggerated to facilitate illustration.

Referring now to the drawings, a desk set such as shown in Figure 1 includes a main base 5 of suitable material, such as metal, marble, wood, or of composite construction,

and a pen socket 6 which is desirably mounted on the base 5 so that the socket can be adjusted, in both horizontal and vertical planes, so that the socket will project the pen in the general direction of a person desiring to use the same. A pen seated in the socket 6 is indicated at 7.

For adjustably mounting the socket as above described, I provide a swivel mounting which includes a base member or ferrule 8 having an internally threaded sleeve part 9 fitting in an opening 10 provided in the main base 5. The ferrule 8 includes the flaring head portion 11 which serves to position the ferrule on the top 12 of the base, and a screw 13 fitting the internally threaded sleeve part 9 serves to prevent upward displacement of the ferrule. The ferrule is preferably clamped tightly in place by tightening the screw 13 so that the ferrule is fixed and cannot rotate relative to the base.

A stem or post 14 is rotatably mounted in the ferrule 8, the post being provided with an enlarged head portion 15 which serves to provide a shoulder 16 for engaging a shoulder 17 provided in the ferrule, thereby to prevent upward displacement of the post. The upper portion 18 of the post 14 is preferably flattened in cross section, as shown in Figures 2 and 3, and provided with an opening 19 for receiving a pivot pin 20.

A hub member 21, preferably cylindrical in form as indicated in Figures 2 and 5, is pivotally mounted on the pivot pin 20, the said hub member being provided with an aperture 22 for receiving the pivot pin, and a slot 23 for receiving the flattened post portion 18. It will be seen that the hub member 21 straddles the flattened post portion 18 and is pivotally mounted thereon so that the hub is adjustable about a horizontal axis.

A sleeve element 24 is disposed around the hub 21, the said sleeve being provided with a slot 25 for receiving the flattened post portion 18, and the said sleeve and hub are interlocked by means of a screw 26 which passes through an aperture 27 in the sleeve and threadedly engages an internally threaded hole 28 in the hub. The screw 26 also serves to secure the socket member 6 to the hub and

sleeve, as clearly shown in Figures 2 and 3.

The sleeve 24 is of larger internal diameter than the external diameter of the hub, and by means of the connecting screw 26 is caused to assume an eccentric position with respect to the hub. It will thus be apparent that the distance from the axis of the pivot pin 20 to the bottom portion 29 of the sleeve is different than the distance from the axis of the said pivot pin to the top or sides of the sleeve, and that the sleeve will be caused to frictionally engage the top surface 30 of the ferrule 8. If desired, the aperture 22 in the hub may be located off-center of the hub so as to permit the use of a hub of fairly large diameter, while at the same time providing the desired amount of space between the hub and sleeve. Also, by using a fairly large hub member, durability of the structure is increased.

As shown in Figures 2 and 3, the parts are arranged so that the hub 21 and sleeve 24 are in contact at their upper portions and so maintained by the screw 26. The eccentric relation between the hub and sleeve and the dimension between the pivot axis and the top 30 are made to be such that the sleeve will have the desired frictional engagement with the top 30 of the ferrule for holding the socket in adjusted position. It will be noted that the engagement between the sleeve and ferrule serves to frictionally hold the socket 6 in vertically adjusted position, i. e., about the axis of the pivot pin 20, and also in horizontally adjusted position, i. e., about the axis of the post 14.

In order to provide for a substantially uniform tension or degree of frictional engagement between the sleeve 24 and the top surface 30 of the base member 8, I arrange the hub member 21 and sleeve 24 with their respective axes disposed relative to each other and relative to said top surface substantially as indicated in the diagram, Fig. 6. It will be seen that the axis 33 of the sleeve 24 is slightly in front of and higher than the pivot axis 34 of the hub 21.

The shortest radius of the sleeve, as it turns about the pivot axis 34, is thus the radii indicated by the arrow 35 and the radius gradually increases on both sides of the said short radius to increased radius indicated by the arrows 36-36.

Thus it appears that there is a looser frictional contact between the sleeve 24 and top 30 when the socket is in vertical position (because the shortest radius 35 is then located between the pivot axis and the top 30) and that the degree of frictional contact will gradually increase as the socket is turned downwardly in either direction. However, as a practical matter, the increased radius length and its normal effect on the frictional contact between said sleeve and top surface, is compensated for by reason of the greater

ease with which the sleeve yields or flexes as a whole to either side of the short radius 35 when the socket is swung towards its horizontal position, as compared with the stiffer resistance to yielding or flexing on both sides of the sleeve as required when the socket is in or near its vertical position.

In short, the variation in resistance of the sleeve to yielding or flexing compensates for the variation in the effective radius of the sleeve and a substantially uniform tension is obtained for holding the socket in adjusted position throughout the range of its adjustment.

Adjustment of the socket 6 about the pivot pin 20 may conveniently be limited by engagement of the bottom 31 of the slot 28 of the hub with either edge of the flattened post portion 18. In this manner, I may conveniently prevent the upper end of the socket from engaging the top surface of the base and thereby possibly scratching or otherwise marring the top surface.

For improving the appearance of the mounting and for preventing displacement of the pivot pin 20, I provide the ends of the pivot pin with screw threading, as indicated in Figure 3, and mount thereon suitable caps or buttons 32-32 which serve to close the opposite sides or ends of the sleeve 24. These buttons 32-32 may be of metal or other suitable material, for instance, suitably colored or mottled bakelite. Obviously, these buttons may be made to match other parts of the pen socket in color and surface configuration without changing the construction of the swivel joint proper. This feature is important, since desk sets of various colors and designs are desirable in the trade.

I have found that the above described mounting is neat in appearance and effective and durable in use, while being inexpensive to manufacture.

I am aware that changes may be made in the structure described without departing from the spirit of my invention, the scope of which should be determined by reference to the following claims, the same being construed as broadly as possible consistent with the state of the art.

I claim as my invention:

1. A swivel mounting for a pen socket, comprising a base member, an axially vertical post mounted in said base member so as to be horizontally rotatable but vertically fixed, axially horizontal means pivotally secured to said post and having engagement with a part of said base member for maintaining said means in adjusted position, and a pen socket secured to said means whereby the socket is horizontally and vertically adjustable in unison with said means and said post respectively.

2. A swivel mounting for a pen socket,

comprising a base member, an axially vertical post mounted in said base member so as to be horizontally rotatable but vertically fixed, axially horizontal means pivotally secured to said post and having yielding engagement with a part of said base member for maintaining said means in adjusted position, and a pen socket secured to said means whereby the socket is horizontally and vertically adjustable in unison with said means and said post respectively.

3. A swivel mounting for a pen socket, comprising a base member, an axially vertical post mounted in said base member so as to be horizontally rotatable but vertically fixed, axially horizontal means pivotally secured to said post, a pen socket carried by said means, and a member also carried by said means having yielding frictional engagement with said base member for maintaining said socket in both horizontally and vertically adjusted position.

4. A swivel mounting for a pen socket, comprising a base member, an axially vertical post mounted in said base member so as to be horizontally rotatable but vertically fixed, an axially horizontal hub member pivotally mounted on said post, a sleeve fitting around said hub and frictionally engaging said base member, a pen-receiving socket, and means uniting said socket and hub member and effective to interlock said hub and sleeve whereby the latter serves to hold said socket in adjusted position as an incident to said frictional engagement.

5. A swivel mounting for a pen socket, comprising a base member, an axially vertical post mounted in said base member so as to be horizontally rotatable but vertically fixed, an axially horizontal hub member pivotally mounted on said post, a sleeve fitting around said hub and frictionally engaging said base member, means interlocking said hub and said sleeve whereby the latter is effective to hold said hub and post in adjusted position as an incident to said frictional engagement, and a pen socket carried by and adjustable with said hub and post.

6. A swivel mounting for a pen socket, comprising a base member, an axially vertical post mounted in said base member so as to be horizontally rotatable but vertically fixed, an axially horizontal hub member pivotally mounted on said post, a sleeve fitting around said hub and frictionally engaging said base member, means interlocking said hub and said sleeve whereby the latter is effective to hold said hub and post in adjusted position as an incident to said frictional engagement, means closing the opposite ends of said sleeve, and a pen socket carried by and adjustable with said hub and post.

7. A swivel mounting for a pen socket comprising a stationary base member, an axially vertical post member mounted in said base

member so as to be horizontally rotatable but vertically fixed, an axially horizontal hub member, a horizontally disposed pivot member connecting the said hub and post whereby said hub is adjustable about said pivot pin, a sleeve fitting around said hub and frictionally engaging said base member, means interlocking said hub and sleeve whereby the latter is effective to hold said hub and post in adjusted position as an incident to said frictional engagement, means mounted on the opposite ends of said pivot pin for closing the opposite ends of said sleeve, and a pen socket carried by and adjustable with said hub.

8. A swivel mounting for a pen socket comprising a base member, an axially vertical post mounted in said base member so as to be horizontally rotatable but vertically fixed, an axially horizontal hub member pivotally mounted on said post, a sleeve fitting around said hub arranged eccentrically relative thereto and frictionally engaging said base member, means interlocking said hub and sleeve whereby the sleeve is effective as an incident to said frictional engagement to hold said hub and post in adjusted position, and a pen socket carried by and adjustable with said hub.

9. A swivel mounting for a pen socket comprising a main base member having an opening therein, a ferrule seated in said opening, a post mounted in said ferrule so as to be horizontally rotatable and held against vertical upward movement, a hub member pivoted on said post, a sleeve fitting loosely around said hub, means uniting said sleeve and hub whereby the sleeve is caused to assume an eccentric position relative to the hub, and thereby to frictionally engage the upper end of said ferrule so as to frictionally hold said hub and post in the desired adjusted position, and a pen socket carried by and adjustable with said hub and post.

10. A swivel mounting for a pen socket comprising a main base member having an opening therein, a ferrule seated in said opening, a post mounted in said ferrule so as to be horizontally rotatable and held against vertical upward movement, a hub member pivoted on said post, a sleeve fitting loosely around said hub, said hub and sleeve being each provided with a slot for receiving said post, whereby said parts straddle the post and are adjustable about the pivot of said hub, means uniting said sleeve and hub whereby the sleeve is caused to assume an eccentric position relative to the hub, and thereby to frictionally engage the upper end of said ferrule so as to frictionally hold said hub and post in the desired adjusted position, and a pen socket carried by and adjustable with said hub and post.

11. A swivel mounting for a pen socket on a base comprising an axially vertical post

rotatably mounted on the base, an axially horizontal pivotal connection between the post and socket, and a single spring device holding said socket in adjusted position both in respect of horizontal adjustment about the axis of said post and in respect of vertical adjustment about the axis of said pivotal connection.
